[57] CLAIM

The ornamental design for a golf putter head, as shown and described.

DESCRIPTION

FIG. 1 is a perspective view of a golf putter head embodying our new design;

FIG. 2 is a front view thereof;

FIG. 3 is a rear view thereof;

FIG. 4 is an end view thereof taken from the end shown in FIG. 1;

FIG. 5 is an end view thereof taken from the end opposite that shown in FIG. 1;

FIG. 6 is a top plan view thereof; and,

FIG. 7 is a bottom plan view thereof.

The characteristic feature of our design resides in the hosel configuration in combination with the particular club head shown.

FIG. 2

FIG. 2

FIG. 3

FIG. 4

FIG. 5

FIG. 6

FIG. 7
